CLAIM

I claim the ornamental design for a notebook computer, as shown and described.

DESCRIPTION

FIG. 1 is a front perspective view of a notebook computer showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another perspective view thereof;

FIG. 9 is an enlarged view of the encircled portion '9' in FIG. 1;

FIG. 10 is an enlarged view of the encircled portion '10' in FIG. 2;

FIG. 11 is an enlarged view of the encircled portion '11' in FIG. 5;

FIG. 12 is an enlarged view of the encircled portion '12' in FIG. 6;

FIG. 13 is an enlarged view of the encircled portion '13' in FIG. 8;

FIG. 14 is a front perspective view of a notebook computer showing my new design with the display screen feature shown in an extended position;

FIG. 15 is a front view thereof;

FIG. 16 is a rear view thereof;

FIG. 17 is a left-side view thereof;

FIG. 18 is a right-side view thereof;

(Continued)

FIG. 19 is a top plan view thereof;
 FIG. 20 is a bottom plan view thereof;
 FIG. 21 is another perspective view thereof;
 FIG. 22 is an enlarged view of the encircled portion '22' in FIG. 14.
 FIG. 23 is an enlarged view of the encircled portion '23' in FIG. 18; and,
 FIG. 24 is an enlarged view of the encircled portion '24' in FIG. 19.
 The even-dash broken lines in the figures depict portions of the notebook computer which form no part of the claimed design.
 The dot-dash broken lines encircling portions of the design represent the extents of the detail views and form no part thereof.

1 Claim, 24 Drawing Sheets
